HINGED CLOSURE

Edward Dolar, Berwyn, Ill.

Application March 20, 1951, Serial No. 216,547

5 Claims. (Cl. 220—31)

1

This invention relates to a novel means for holding a cover in closed position on a container and more particularly to a cam means for holding a cover in closed position on a container.

At the present time in most covers for containers a coil spring is utilized to hold the cover over the open end of the container. This coil spring is usually circumposed about the axis pivotally connecting the cover to the container. The free ends of a coil spring of this type frequently jump out of place and result in the spring exerting absolutely no force at all. Thus, the cover will not stay on the open end of the container. From the foregoing it will be seen that coil springs are unsatisfactory for holding a cover in closed position on a container.

An object of the present invention is to provide a novel means for holding a cover in closed position on a container.

A further object of the present invention is to provide a means for holding a cover in closed position on a container in which no springs are used.

A further object of the present invention is to provide a cam means for holding a cover in closed position on a container.

Another object of the present invention is to provide a means for connecting a cover to a container which is of a very simple construction and having a minimum number of parts.

Another object of the present invention is to provide a means for connecting a cover to a container which is sturdy and durable in construction, reliable and efficient in operation, and simple and inexpensive to manufacture.

Other objects and advantages will be apparent from the following description taken in conjunction with the accompanying drawing.

For a full and complete understanding of the invention, reference is made to the following description and accompanying drawing wherein:

Figure 1 is a side elevational view of the cam means of the present invention shown holding a cover in closed position on a container.

Figure 2 is a back elevational view of the cam means of the present invention shown holding a cover in closed position on a container.

Figure 3 is a back elevational view showing a part of the novel cam means of the present invention assembled on a container, the cover and parts associated therewith being removed; and

Figure 4 is a bottom view of the cover and the cam means associated therewith.

Referring specifically to the drawing, wherein the same reference characters are used through-

2

out the several views to designate the same or similar parts, the numeral 1 designates a container fabricated of glass or other suitable material and having one end open and the other end closed. The open end of the container 1 has a neck which is integrally secured to the container 1, the neck not being shown in the drawing. The neck is provided with a plurality of threads on its outer face.

10 A cap 2 fabricated of metal, Bakelite or other suitable material is positioned on the open end of the container 1. The cap 2 comprises a top 3 having a plurality of perforations therein, the perforations in the top 3 not being shown in the drawing. Extending around the periphery of the top 3 is a flange 4 which projects away from the top 3 of the cap 2. The flange 4 of the cap 2 has a plurality of internal threads on its inner face which are in threaded engagement with the threads on the outer face of the neck when the cap 2 is positioned on the container 1, the internal threads on the cap 2 not being shown in the drawing. The container 1 is adapted to be used as a condiment holder and is adapted to contain such condiments as salt or pepper.

Proceeding to the novel feature in applicant's invention the outer face of the circular flange 4 of the cap 2 has a groove 5 which extends there-around. Surrounding the cap 2 and adapted to seat in the groove 5 is a resilient member or band 6 fabricated of metal or other suitable material which has ends 7 and 8 in spaced relation with respect to each other. A first extension 9 fabricated of metal or other suitable material has one end 10 which is arranged in end to end relation with respect to the end 7 of the resilient member or band 6, the first extension 9 being integrally secured to the resilient member or band 6, and a second extension 11 fabricated of metal or other suitable material has one end 12 which is arranged in end to end relation with respect to the end 8 of the resilient member or band 6, the second extension 11 being integrally secured to the resilient member or band 6. The first extension 9 and the second extension 11 are arranged in spaced parallel relation with respect to each other and project away from the flange 4 of the cap 2.

40 A first leg 13 fabricated of metal or other suitable material has one end 14 which is arranged in end to end relation with respect to the other end 15 of the first extension 9 and is integrally secured to the first extension 9. A second leg 16 fabricated of metal or other suitable material has one end 17 which is arranged in end to end relation with respect to the other end 18 of the

second extension 11 and is integrally secured to the second extension 11. The first leg 13 and the second leg 16 are arranged in diverging or flared relation with respect to each other, the ends 14 and 17 being the converging ends and the other ends 19 and 20 being the diverging ends. Further, the first leg 13 and the second leg 16 extend at right angles from the first extension 9 and the second extension 11.

A first pin 21 is arranged in end to end relation with respect to the end 19 of the first leg 13 and is positioned at right angles with respect to the first leg 13 and is integrally secured thereto. A second pin 22 is arranged in end to end relation with respect to the end 20 of the second leg 16 and is positioned at right angles with respect to the second leg 16 and is integrally secured to the second leg 16. The first pin 21 and the second pin 22 are arranged in longitudinal aligned spaced relation with respect to each other and project away from each other.

An auxiliary cover 23 fabricated of metal or other suitable material carries a finger tab 24 at one edge of its periphery which is integrally secured to the auxiliary cover 23. A third extension 25 fabricated of metal or other suitable material has one end integrally secured to the edge of the periphery of the auxiliary cover 23 opposite the finger tab 24 and the third extension 25 projects away from the auxiliary cover 23 but lies in the same plane as the auxiliary cover 23. A lever 26 has one end which is arranged in end to end relation with respect to the other end of the third extension 25 and is integrally secured thereto, the lever 26 being positioned at right angles with respect to the auxiliary cover 23 and the third extension 25. The lever 26 tapers from said one end toward its other end. A slot 27 extends inwardly from said other end of the lever 26 and terminates at a point spaced from said one end of the lever 26.

The longitudinal center line of the third extension 25 and the lever 26 is stamped or protruded outwardly to form a rib 28. This rib 28 terminates in communication with the slot 27. The rib 28 provides a means of strengthening and reinforcing the third extension 25 and the lever 26, the third extension 25 and the lever 26 being made of a rather thin material. A first flange 29 fabricated of metal or other suitable material is integrally secured to one side of the lever 26 and a second flange 30 fabricated of metal or other suitable material is integrally secured to the other side of the lever 26. The first flange 29 and the second flange 30 both project away from one face of the lever 26 and the first flange 29 and the second flange 30 are bent toward each other. Since the lever 26 tapers from said one end thereof toward said other end thereof, this results in the first flange 29 and the second flange 30 being arranged in converging spaced relation with respect to each other.

The first flange 29 and the second flange 30 are provided with aligned openings 31 and 32 respectively, the opening 31 being adapted to receive the first pin 21 and the opening 32 being adapted to receive the second pin 22. It is to be emphasized that the first leg 13, the second leg 16, the third extension 25, the lever 26, the first flange 29, and the second flange 30 should all possess a certain degree of resiliency.

Mode of operation

Assuming the device to be completely disassembled, the cap 2 is first threaded onto the neck

of the container 1. Next, the resilient member or band 6 is positioned in the groove 5. Then, the first pin 21 is inserted in the opening 31 of the flange 29 and the second pin 22 is inserted in the opening 32 of the flange 30. Assuming the auxiliary cover 23 to be out of closed position with respect to the top 3 of the cap 2, the auxiliary cover 23 is rotated about the first pin 21 and the second pin 22. As the rotation continues the first flange 29 and the second flange 30 engage the first leg 13 and the second leg 16 respectively urging the first leg 13 and the second leg 16 toward each other. As the rotation of the auxiliary cover 23 is further continued, the converging relation of the first flange 29 and the second flange 30 with respect to each other causes a gradual increasing force to be exerted on the first leg 13 and the second leg 16.

Upon the auxiliary cover 23 being placed upon the top 3 of the cap 2 the first flange 29 will be in parallel relation with the first leg 13 and the second flange 30 will be in parallel relation with the second leg 16. Further, upon the auxiliary cover 23 being placed upon the top 3 of the cap 2, the first leg 13 will seat in a corner 33 at the intersection of the first flange 29 and the lever 26, and the second leg 16 will seat in a corner 34 at the intersection of the second flange 30 and the lever 26. It will thus be seen that there is a cam action between the first leg 13, the second leg 16, the lever 26, the first flange 29, and the second flange 30 which will snugly and firmly hold the auxiliary cover 23 upon the top 3 of the cap 2 so that no condiment such as salt or pepper can escape through the perforations in the top 3 of the cap 2.

The above description hereinbefore set forth is merely the best mode of practicing the present invention, as there are many modifications and slight deviations still within the spirit and scope of the present invention which are too numerous to mention. It is the applicant's intention to include every modification and deviation of the present invention that is within the length, breadth, and scope of the appended claims.

What is claimed is:

1. Means for connecting a cover to a container having one end open, said cover being adapted to be positioned over said open end of said container, said means comprising a pair of legs arranged in converging spaced relation with respect to each other and one of said legs having its converging end secured to said container adjacent the open end thereof and the other of said legs having its converging end secured to said container adjacent the open end thereof, a lever having one end secured to said cover and having its other end pivotally connected to the other ends of said pair of legs, a first flange positioned on one side of said lever and secured thereto, and a second flange arranged in converging spaced relation with respect to said first flange and positioned on the other side of said lever and secured thereto, the converging ends of said first flange and said second flange being positioned adjacent the converging ends of said pair of legs when said cover is in closed position over said open end of said container, said flanges being bent toward one another whereby said first flange frictionally engages said one of said pair of legs and said second flange frictionally engages said other of said pair of legs when said cover is in closed position on said open end of said container.
2. Means for connecting a cover to a container

having one end open, said cover being adapted to be positioned over said open end of said container, said means comprising a pair of legs arranged in converging spaced relation with respect to each other and one of said legs having its converging end secured to said container adjacent said open end thereof, and the other of said legs having its converging end secured to said container adjacent said open end thereof, a lever having one end secured to said cover, said lever being provided with a slot extending inwardly from the other end thereof, said other end of said lever being pivotally connected to the other ends of said pair of legs, a first flange positioned on one side of said lever and secured thereto, and a second flange arranged in converging spaced relation with respect to said first flange and positioned on the other side of said lever and secured thereto, the converging ends of said first flange and said second flange being positioned adjacent the converging ends of said legs when said cover is in closed position over said open end of said container.

3. In a container having one end open and being provided with a groove extending around the outer face thereof adjacent the open end thereof and a cover positioned on said open end of said container, a band positioned in said groove and having its ends spaced from each other, a pair of legs arranged in converging spaced relation with respect to each other and one of said legs having its converging end secured to one end of said band and the other of said legs having its converging end secured to the other end of said band, a lever arranged at right angles with respect to said cover and having one end secured to the periphery of said cover, the other end of said lever being pivotally connected to the other ends of said pair of legs, a first flange positioned on one side of said lever and secured thereto, and a second flange arranged in converging spaced relation with respect to said first flange and positioned on the other side of said lever and secured thereto, said first and second flanges being bent toward each other and said first flange embracing said one of said legs and said second flange embracing said other of said legs when said cover is in closed position over said open end of said container.

4. In a container having one end open and being provided with a groove extending around the outer face thereof adjacent the open end thereof and a cover positioned on said open end of said container, a band positioned in said groove and having its ends spaced from each other, a pair of legs arranged in converging spaced relation with respect to each other and one of said legs having its converging end secured to one end of said band and the other of said legs having its converging end secured to the other end of said band, a lever arranged at right angles with respect to said cover and having one end secured to the periphery of said cover, said lever being

provided with a slot extending inwardly from the other end thereof, said other end of said lever being pivotally connected to the other ends of said pair of legs, a first flange positioned on one side of said lever and secured thereto, and a second flange arranged in converging spaced relation with respect to said first flange and positioned on the other side of said lever and secured thereto, said first and second flanges being bent toward each other and said first flange embracing said one of said legs and said second flange embracing said other of said legs when said cover is in closed position over said open end of said container, said flanges and said legs extending in the same longitudinal direction when said cover is in closed position, the converging ends of said first flange and said second flange being positioned adjacent the converging ends of said pair of legs when said cover is in closed position on said open end of said container.

5. In a container having one end open and being provided with a groove extending around the outer face thereof adjacent the open end thereof and a cover positioned on said open end of said container, a band positioned in said groove and having its ends spaced from each other, a first extension having one end secured to one end of said band, a second extension arranged in spaced parallel relation with respect to said first extension and having one end secured to the other end of said band, said first extension and said second extension projecting away from said container, a pair of legs arranged in converging spaced relation with respect to each other and one of said legs having its converging end secured to the other end of said first extension and the other of said legs having its converging end secured to the other end of said second extension, a third extension having one end secured to the periphery of said cover, a lever arranged at right angles with respect to said cover and said third extension and having one end secured to the other end of said third extension, said lever being provided with a slot extending inwardly from the other end thereof, said other end of said lever being pivotally connected to the other ends of said pair of legs, a first flange positioned on one side of said lever and secured thereto, a second flange arranged in converging spaced relation with respect to said first flange and positioned on the other side of said lever and secured thereto, said first and second flanges being bent toward each other, said flanges and said legs extending in the same longitudinal direction when said cover is in closed position, the converging ends of said first flange and said second flange being positioned adjacent the converging ends of said pair of legs and said first flange embracing said one of said pair of legs and said second flange embracing said other of said pair of legs when said cover is in closed position over said open end of said container.
